UNITED STATES PATENT OFFICE

CONYERS BUTTON, OF PHILADELPHIA, PENNSYLVANIA.

DESIGN FOR STOCKING FABRIC.

Specification forming part of Design No. 6,670, dated May 27, 1873; application filed May 13, 1873.

To all whom it may concern:

Be it known that I, CONYERS BUTTON, of Philadelphia, Pennsylvania, have invented a Design for Stocking Fabric, of which the following is a specification:

The nature of my design is clearly illustrated by the figure in the accompanying drawing. It consists of stripes A and B, alternated upon a plain ground, *a*. Each stripe A has a central longitudinal rib, *b*, and upon each side of the same a series of narrower ribs or bars, *c*, *d*, *e*, *f*, *g*, and *h*, arranged as shown. The stripe B is narrower than the stripe A, but is similarly composed of a series of minor stripes, bars, or ribs, the outer

most of which are the widest. The central rib *i* of the stripe B may be of a shade or color different from that of the ribs at either side of the same.

Irrespective of the colors employed, I claim—

The design for a stocking fabric, substantially as described, and as represented in and by the accompanying drawing.

In testimony whereof I have signed my name to this specification in the presence of two subscribing witnesses.

CONYERS BUTTON.

Witnesses:

W.M. A. STEEL,
L. BOSWELL.
